UNITED STATES PATENT OFFICE.

URIAH DAVIS, OF PARK RIDGE, ILLINOIS.

HUMIDIFIER.

1,190,223.

Specification of Letters Patent.

Patented July 4, 1916.

Application filed August 5, 1915. Serial No. 43,788.

To all whom it may concern:

Be it known that I, URIAH DAVIS, a citizen of the United States, residing at Park Ridge, in the county of Cook and State of Illinois, have invented a certain new and useful Improvement in Humidifiers, of which the following is a full, clear, concise, and exact description, reference being had to the accompanying drawings, forming a part of this specification.

My invention relates to humidifiers, and has for its object the provision of a device of this character which is designed for use in connection with a radiator or register from whence hot air issues, the object being to cause the hot air during its movement to absorb moisture, thereby to have the air in the room of the proper humidity.

My invention is designed to wash the air at the same time and to collect the dust, thus to provide a cleaner atmosphere for the occupants of the room.

My invention contemplates the provision of apparatus by virtue of which a very large evaporation may be caused, it being possible with my improved device to evaporate one gallon of water throughout a period of eight hours with the radiator at 120° F.

I will describe several forms which my invention may take more in detail by referring to the accompanying drawings, in which—

Figure 1 is a perspective view of my improved device mounted on top of a radiator; Fig. 2 is a longitudinal sectional view on line *a—a* of Fig. 3; Fig. 3 is a sectional view on line *b—b* of Fig. 2; Fig. 4 is a sectional view on line *c—c* of Fig. 2; Fig. 5 is a vertical sectional view of a modified form of the device shown in connection with a wall register; Fig. 6 is a similar view of my device shown in connection with a floor register, and Fig. 7 is a detail perspective view of the adapter used in connection with the structure of Fig. 6.

Referring more particularly to Figs. 1, 2, 3 and 4, I show a radiator 1 which my improved humidifier 2 is adapted to surmount as shown in Fig. 1.

My improved device detailed more particularly in Figs. 2, 3 and 4 comprises a dish or water tank 3 which has upwardly extending sides 4, 4. A front wall 5 perforated as shown by having the holes 6 is fastened to the front of the tank 3 and extends upwardly, thus forming a three-sided enclosure above the tank. Two deflectors 7

and 8 extend as shown more clearly in Fig. 2 toward the right or open side of this three-sided structure above the water tank, and are fastened respectively to the sides and front wall 4, 5. The deflecting plate 7 stops at 9 as shown, whereas the deflecting plate 8 has ribs 10 extending forwardly as shown more clearly in Figs. 2 and 3. A pivoted cover plate 11 is hinged at 9 as shown more clearly in Fig. 2. Suitable rods 12 are mounted in place across the upper portion of the structure and suitable rods 13 are mounted in place along the lower portion thereof. These rods serve for the purpose of supporting a suitable absorbent carrier 14 such for instance as terry cloth, which is wound over the rods as shown more clearly in Fig. 3. This cloth 14 thus extends into the liquid within the tank 3 and also extends upwardly therefrom into the path of the hot air as indicated by the arrows 15, 16 in Fig. 2.

It will be seen that the hot air from the radiator passes upwardly along both sides of the deflector 8, and passes by the strips 14 from where it issues through the openings 6 into the atmosphere of the room in a washed, dust-free, and humidified condition.

A plate 24 is fastened within the casing as shown in Fig. 3 which provides a channel through which liquid may be poured into the tank 3.

Referring more particularly to Fig. 5, I show my improved device as applied to a wall register. This wall register is shown at 17, and hot air issues therefrom as indicated by the arrows. My improved device is placed in front of the structure, all parts being the same as shown in Figs. 1 to 4 with the exception that the baffle plates 7 and 8 are omitted, an extension tube 18 however being provided which extends from the register to the device to direct the hot air therethrough in a way similarly as is done by the baffle plates 7 and 8 in the structure of the Figs. 1 to 4.

In Figs. 6 and 7, I show the device as applied to an opening 19 through which hot air issues from the floor. My improved device in this instance is similar to the device shown in Figs. 1 to 4, but is mounted in place upon an adapter 20 shown in perspective in Fig. 7. This adapter has a shelf 21 upon which the device rests, and has side walls 22 inclined at 23 to accommodate the inclined ends of the side walls running along the deflector plates 7 and 8.

In the claims I use the word radiator to mean not only the iron radiator as ordinarily understood, but also a register through which hot air issues.

5 From what has been thus described it is thought the nature of my invention will be readily clear to those skilled in the art.

Having however thus described several forms which my invention may take, what 10 I claim as new and desire to secure by Letters Patent is:—

1. In a device of the character described the combination with a tank adapted to contain liquid, of absorbent means projecting 15 into and extending upwardly from said liquid, a ventilated casing for said means, said casing and tank forming a self-contained structure adapted to rest upon a radiator, and a pair of deflecting plates secured 20 to said structure adapted to direct the hot air through said casing past different portions of said absorbent means.

2. In a device of the character described the combination with a tank adapted to contain liquid, of a plurality of parallel rows 25 of absorbent means projecting into and extending upwardly from said liquid, a ventilated casing for said means, said casing and tank forming a self-contained structure adapted to rest upon a radiator, and a pair 30 of deflecting plates secured to said structure adapted to direct the hot air through said casing past different portions of said absorbent means.

3. In a device of the character described the combination with a tank adapted to contain liquid, of a plurality of parallel rows 35 of absorbent means projecting into and extending upwardly from said liquid, a ventilated casing for said means, said casing and tank forming a self-contained structure adapted to rest upon a radiator, and a deflecting plate secured to said structure adapted to direct the hot air through said casing 40 past said absorbent means, said deflecting plate extending unbroken up to said means and having a plurality of extending fingers 45 extending between the said parallel rows.

4. In a device of the character described the combination with a tank adapted to contain liquid, of a plurality of parallel rows 50 of absorbent means projecting into and extending upwardly from said liquid, a ventilated casing for said means, said casing and tank forming a self-contained structure adapted to rest upon a radiator, a deflecting plate secured to said structure adapted to direct the hot air through said casing past 55 said absorbent means, said deflecting plate extending unbroken up to said means and having a plurality of extending fingers 60 extending between the said parallel rows, and

a second deflector plate exteriorly of said first aforesaid deflector plate and terminating substantially at the top of said casing. 65

5. In a device of the character described the combination with a tank adapted to contain liquid, of a plurality of parallel rows of absorbent means projecting into and extending upwardly from said liquid, a ventilated 70 casing for said means, said casing and tank forming a self-contained structure adapted to rest upon a radiator, a deflector plate secured to said structure adapted to direct the hot air through said casing past 75 said absorbent means, said deflector plate extending unbroken up to said means and having a plurality of extending fingers extending between the said parallel rows, a second deflector plate exteriorly of said first 80 aforesaid deflector plate and terminating substantially at the top of said casing, and a channel provided in said casing leading to said tank.

6. In a device of the character described 85 the combination with a tank adapted to contain liquid, of a plurality of parallel rows of absorbent means projecting into and extending upwardly from said liquid, a ventilated casing for said means, said casing and 90 tank forming a self-contained structure adapted to rest upon a radiator, a deflector plate secured to said structure adapted to direct the hot air through said casing past said absorbent means, said deflector plate 95 extending unbroken up to said means and having a plurality of extending fingers extending between the said parallel rows, a second deflector plate exteriorly of said first aforesaid deflector plate and terminating substantially at the top of said casing, a 100 channel provided in said casing leading to said tank, and a hinged cover plate for said casing.

7. In a device of the character described 105 the combination with a tank adapted to contain liquid, of absorbent means projecting into and extending upwardly from said liquid, a ventilated casing for said means, said casing and tank forming a self-contained structure adapted to rest upon a radiator, means to direct the hot air from 110 said radiator through said casing past said absorbent means, said absorbent means consisting of a long strip of absorbent material, and supports some within and some without said liquid about which said absorbent means is wound to and fro.

In witness whereof, I hereunto subscribe my name this 9th day of July, A. D., 1915. 120
URIAH DAVIS.
